UNITED STATES PATENT OFFICE.

DAVE WINBRAY, OF HOT SPRINGS, ARKANSAS.

AERATING DEVICE.

1,150,238.

Specification of Letters Patent. Patented Aug. 17, 1915.

Application filed February 6, 1915. Serial No. 6,643.

To all whom it may concern:

Be it known that I, DAVE WINBRAY, a citizen of the United States, residing at Hot Springs, in the county of Garland and State of Arkansas, have invented certain new and useful Improvements in Aerating Devices, of which the following is a specification, reference being had to the accompanying drawings.

10 This invention relates to certain improvements in aerating devices and has relation more particularly to a device of this general character especially designed and adapted for use in connection with the treatment of 15 the scalp; and it is an object of the invention to provide a device of this general character having novel and improved means whereby air under pressure is caused to pass through a suitable medicated fluid whereby 20 said fluid will be atomized.

The invention consists in the details of construction and in the combination and arrangement of the several parts of my improved aerating device whereby certain important advantages are attained and the 25 device is rendered simpler, less expensive and otherwise more convenient and advantageous for use, all as will be hereinafter more fully set forth.

30 The novel features of the invention will be carefully defined in the appended claims.

In order that my invention may be the better understood, I will now proceed to describe the same with reference to the accompanying drawings, wherein is disclosed a view, partly in elevation and partly in section, of an aerating device constructed in accordance with an embodiment of my invention.

40 As disclosed in the accompanying drawings, 1 denotes a reservoir or container having a filling opening 2 at one end adapted to be closed by the cap 3, said cap being provided with a discharge opening 4 in communication with the flexible tube 5 leading through the discharge member 6, herein disclosed as a comb of hollow construction, the teeth 7 whereof having their extremities open whereby it will be readily perceived 45 that the air leading from within the container or reservoir 1 may be properly applied to the scalp. As the comb in its details, other than the teeth having their free extremities open, forms no part of my invention, it is not believed that a further description thereof is necessary.

Positioned within the container or reservoir 1 is a substantially U-shape pipe 8 having one extremity disposed exteriorly of the container through the top thereof, said exterior or projected portion being suitably connected with the conduit 9 leading from a suitable source of air supply under pressure. As the source of air supply under pressure may be of a character dictated by 60 conditions, I do not wish to be understood as limiting myself in this respect in any way, although in practice I have found it best to have the air delivered through the conduit 9 under a pressure of substantially 65 nine pounds per square inch.

The second stem of the pipe 8 terminates slightly above the bend 11 and has engaged therewith the nozzle 12 and disposed within the stem 10 and terminating below the upper extremity thereof is the intake pipe 14 arranged in parallelism with the stems of the pipe 8 and terminating therebelow and in close proximity to the base of the container or reservoir 1 and also terminating 75 above the water line within the reservoir, whereby it will be seen that the force of the air through the pipe 8 will draw the liquid within the container or reservoir upwardly through the intake pipe 14 and force 80 the same through the nozzle 12.

Positioned directly above the nozzle 12 at a predetermined distance therefrom is the convex member 15 which deflects the stream emitted from the nozzle 12 and serves particularly to break the liquid into minute particles so that the same will be forced through the tube 5 in substantially the nature of a vapor so that the discharge from the comb member is substantially dry. It will 90 also be readily perceived that the member 15 will cause the heavy particles of the fluid to be thrown downwardly to the initial supply of fluid within the reservoir or container.

In practice the fluid F is intended to be 100 suitably medicated. As herein embodied, the member 15 is maintained in operative position through the medium of the diametrically opposed straps 16, the lower extremities whereof being connected with an 105 annular member 17 adapted to surround and bear against the nozzle 12, while the upper extremities thereof are engaged with the annular member 18 adapted to be suitably engaged within the discharge opening 4.

In the present embodiment of my invention, the intake pipe 14 is suitably disposed

through the curved portion 11 of the pipe 8 and has its extremity within the stem 10 reinforced or braced by the transverse arm 19 intersecting the bore of the stem 10 and having its central portion provided with a suitable opening through which the intake pipe 14 projects, the walls of said opening frictionally engaging the periphery of the pipe 14.

10 From the foregoing description, it is thought to be obvious that an aerating device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

25 I claim.

1. A device of the character described including a reservoir, a discharge member in communication therewith at the top thereof, 30 a U-shape pipe within the reservoir, one stem thereof projecting through the top of the reservoir, the second stem of the pipe being of less length than the first named stem, the projected extremity of said stem 35 being adapted for communication with a source of air under pressure, a discharge nozzle carried by the free extremity of the second stem of the U-shape pipe, a member positioned directly above the nozzle and 40 having its opposed face convexed, and an intake pipe projecting within the second stem of the U-shape pipe and leading from a point in close proximity to the bottom of the reservoir.

45 2. A device of the character described including a reservoir, a discharge member in communication therewith at the top thereof, a U-shape pipe within the reservoir, one stem thereof projecting through the top of 50 the reservoir, the second stem of the pipe being of less length than the first named stem, the projected extremity of said stem 55 being adapted for communication with a source of air under pressure, a discharge nozzle carried by the free extremity of the second stem of the U-shape pipe, a member positioned directly above the nozzle and 60 having its opposed face convexed, an intake pipe projecting within the second stem of the U-shape pipe and leading from a point in close proximity to the bottom of the reservoir, and means coacting with the nozzle for maintaining the member in applied position.

65 3. A device of the character described in-

cluding a reservoir, a discharge member in communication therewith at the top thereof, a U-shape pipe within the reservoir, one stem thereof projecting through the top of the reservoir, the second stem of the pipe being of less length than the first named stem, the projected extremity of said stem being adapted for communication with a source of air under pressure, a discharge nozzle carried by the free extremity of the second stem of the U-shape pipe, a member positioned directly above the nozzle and having its opposed face convexed, an intake pipe projecting within the second stem of the U-shape pipe and leading from a point in close proximity to the bottom of the reservoir, and means coacting with the nozzle and the container for maintaining the member in applied position.

4. A device of the character described including a reservoir, a discharge member in communication therewith at the top thereof, a U-shape pipe within the reservoir, one stem thereof projecting through the top of the reservoir, the second stem of the pipe 70 being of less length than the first named stem, the projected extremity of said stem being adapted for communication with a source of air under pressure, a discharge nozzle carried by the free extremity of the 75 second stem of the U-shape pipe, a member positioned directly above the nozzle and having its opposed face convexed, an intake pipe projecting within the second stem of the U-shape pipe and leading from a point in close proximity to the bottom of the reservoir, and means coacting with the nozzle and the container for maintaining the member in applied position.

5. A device of the character described including a reservoir, a discharge member in communication therewith at the top thereof, 80 a U-shape pipe within the reservoir, one stem thereof projecting through the top of the reservoir, the second stem of the pipe 85 being of less length than the first named stem, the projected extremity of said stem being adapted for communication with a source of air under pressure, a discharge nozzle carried by the free extremity of the 90 second stem of the U-shape pipe, a member positioned directly above the nozzle and having its opposed face convexed, an intake pipe projecting within the second stem of the U-shape pipe and leading from a point in close proximity to the bottom of the reservoir, an annular member surrounding and contacting with the nozzle, and upstanding arms carried by the annular member and 95 engaging the first named member for maintaining the first named member in applied 100 position.

5. A device of the character described including a reservoir, a discharge member in communication therewith at the top thereof, 110 a U-shape pipe within the reservoir, one stem thereof projecting through the top of the reservoir, the second stem of the pipe 115 being of less length than the first named stem, the projected extremity of said stem being adapted for communication with a source of air under pressure, a discharge nozzle carried by the free extremity of the 120 second stem of the U-shape pipe, a member positioned directly above the nozzle and having its opposed face convexed, an intake pipe projecting within the second stem of the U-shape pipe and leading from a point in close proximity to the bottom of the reservoir, an annular member surrounding and 125 contacting with the nozzle, and upstanding arms carried by the annular member and engaging the first named member for maintaining the first named member in applied 130 position, said arms extending above the first

named member and being secured to the reservoir.

6. A device of the character described including a reservoir, a discharge member in communication therewith at the top thereof, a pipe projecting within the reservoir and having its interior free portion vertically disposed and directed upward, said pipe being adapted for communication with a source of air under pressure, a discharge nozzle carried by the free extremity of the pipe within the reservoir, a member positioned directly above the nozzle and having its opposed face convexed, and an intake pipe projecting within the said vertical portion of the pipe within the reservoir and leading from a point in close proximity to the bottom of the reservoir.
7. A device of the character described including a reservoir, a discharge member in communication therewith at the top thereof, a pipe projecting within the reservoir and having its interior free portion vertically disposed and directed upward, said pipe being adapted for communication with a source of air under pressure, a discharge nozzle carried by the free extremity of the pipe within the reservoir, a member positioned directly above the nozzle and having its opposed face convexed, an intake pipe projecting within the said vertical portion of the pipe within the reservoir and leading from a point in close proximity to the bottom of the reservoir, and means coacting with the nozzle for maintaining the member in applied position.

8. A device of the character described comprising a reservoir, a discharge member in communication therewith at the top thereof, a pipe projecting within the reservoir and having its interior free portion vertically disposed and directed upward, said pipe being adapted for communication with a source of air under pressure, a discharge nozzle carried by the free extremity of the pipe within the reservoir, a member positioned directly above the nozzle and having its opposed face convexed, an intake pipe projecting within the said vertical portion of the pipe within the reservoir and leading from a point in close proximity to the bottom of the reservoir, and means coacting

with the nozzle and the container for maintaining the member in applied position.

9. A device of the character described including a reservoir, a discharge member in communication therewith at the top thereof, a pipe projecting within the reservoir and having its interior free portion vertically disposed and directed upward, said pipe being adapted for communication with a source of air under pressure, a discharge nozzle carried by the free extremity of the pipe within the reservoir, a member positioned directly above the nozzle and having its opposed face convexed, an intake pipe projecting within the said vertical portion of the pipe within the reservoir and leading from a point in close proximity to the bottom of the reservoir, an annular member surrounding and contacting with the nozzle, and upstanding arms carried by the annular member engaging the first named member for maintaining the first named member in applied position.

10. A device of the character described including a reservoir, a discharge member in communication therewith at the top thereof, a pipe projecting within the reservoir and having its interior free portion vertically disposed and directed upward, said pipe being adapted for communication with a source of air under pressure, a discharge nozzle carried by the free extremity of the pipe within the reservoir, a member positioned directly above the nozzle and having its opposed face convexed, an intake pipe projecting within the said vertical portion of the pipe within the reservoir and leading from a point in close proximity to the bottom of the reservoir, an annular member surrounding and contacting with the nozzle, and upstanding arms carried by the annular member engaging the first named member for maintaining the first named member in applied position, said arms extending above the first named member and being secured to the reservoir.

In testimony whereof I hereunto affix my signature in the presence of two witnesses. 100
DAVE WINBRAY.
